UNITED STATES PATENT OFFICE.

BENJAMIN BIRKENFIELD, OF DEAL, NEW JERSEY.

WOMAN'S UNDERGARMENT.

1,277,839.

Specification of Letters Patent.

Patented Sept. 3, 1918.

Application filed February 17, 1917. Serial No. 149,844.

To all whom it may concern:

Be it known that I, BENJAMIN BIRKENFIELD, citizen of the United States, residing at Deal, in the county of Monmouth and State of New Jersey, have invented certain new and useful Improvements in Women's Undergarments, of which the following is a specification, reference being had therein to the accompanying drawing.

10 This invention relates to improvements in undergarments for women, and has especial reference to improvements in under-skirts, adapted at times, in keeping with the wish of the wearer, to be adjusted in simulation of drawers.

Characteristic features of a garment made in accordance with the present invention reside in its capability to normally, as a skirt, present the appearance of the ordinary or conventional short endless skirt entirely encompassing the body of the wearer, and, when properly adjusted to close between the legs, will possess substantially concealed fastenings to present in effect apparently individual or separate continuous leg portions.

Another important advantage to be derived from the preferred embodiment of the invention flows from the formation of the garment so that, when closed to constitute drawers or leg portions, the inner meeting or adjacent side edges of the legs will in fact be free or relatively unsecured, conveniently from the crotch to the bottoms of the legs, so that, without unfastening the garment, 35 either leg portion may be drawn across the body of the wearer for all sanitary purposes, the leg portions being of substantial width to themselves facilitate this desirable result, and the said unsecured inner edges thereof 40 being adapted to readily spread apart to correspondingly afford abundantly ample opening for adjusting and protecting the leg portions when occasion requires.

The garment of course possesses still other subsidiary advantages in that, for the purposes stated, the same as drawers, need not necessarily be manipulated in the manner to which I have alluded, because of its permitting an easy restoration to skirt-formation 50 should emergency demand, and again closed if desired, notwithstanding the wearer may be fully dressed. Also, when being laundered, in its fully open or skirt state, the garment is easily handled and treated, avoiding the usual necessity of slipping the same over the customary ironing board, in that all

portions of the skirt may be laid flat on the surface of the board without obstruction or interference, and ironed in that condition.

For the purpose of imparting a better 60 understanding of the invention, that preferred embodiment of the same, previously referred to herein, will be illustrated in the accompanying drawings forming part hereof.

65 In the drawings:

Figures 1 and 2 are, respectively, front and rear views of the skirt in its expected open condition;

70 Figs. 3 and 4 are similar views of the same in closed or drawers-like condition;

Fig. 5 is a vertical, central, sectional view on the line $z-z$ of Fig. 1;

Fig. 6 is a view like Fig. 5, on the line $z-z$ of Fig. 3, and,

75 Figs. 7 and 8 are, respectively, lower end views of the garment as shown in Figs. 1 and 3.

Referring more specifically to the drawings, wherein the same reference letters represent the identical parts in the several views,—A indicates the front and B the back of the skirt formed of pieces of muslin or other suitable material stitched together to provide a circumferentially continuous body part of such fullness of material to be of bell-shape, when open and spread. This body, at its upper end is slit for a short depth at opposite sides of the garment, as at C, the purpose of which is merely to facilitate the adjusting of the skirt to the wearer, convenient fastenings, as buttons D and button-holed portions E, affording suitable connections at the waist-band, the forepart F of the latter being preferably in elastic, while the back part G is shirred to confine a suitable elastic strip J, for obvious purposes.

The body portion A—B of the skirt terminates approximately at the line K, and 100 stitched therearound at opposite sides are the ruffle extensions L and M, each extending around one side of the skirt and about one-half of the front and rear portions thereof, whereby the adjacent ends or edges 105 of the pair of oppositely disposed ruffles terminate at the center of the front and back for purposes as will soon more fully appear.

Intermediate of the back adjacent edges 110 of the ruffle extensions, and but slightly thereabove, that is, generally in line with the bottom edge of the continuous body por-

tion B, I provide separable fastening devices, for instance, buttons N, conveniently three in number, with the middle button arranged rearmost and the outside buttons approximately in line with the said edges of the ruffle extensions.

To coöperate with the separable fastening devices N, to which I have just alluded, a narrow-width flap O is provided on the body portion A similarly located between the forward adjacent edges of the ruffle extensions, the secured edge of this flap being in line with said adjacent edge portions, and having outside button-holes Q disposed parallel therewith to engage the corresponding buttons N, and a central button-hole R to engage the middle button N, when it is desired to close the skirt below the crotch for drawers formation.

The front and back portions A and B of the skirt, adjoining the separable fastening elements are given a fullness of material, as at S and T, so that the same may be turned in opposite directions inwardly beneath the crotch of the wearer and there fastened so that the united edges are effectively hidden below said crotch. It is also to be noted that the width of the little flap O is insignificant, as compared to the depth of the ruffle extensions, so as to never project therebelow, and by reason of this fact, coupled with the soft, highly flexible nature of the material of which the skirt is formed, and the fullness thereof, as at S and T, the separable fastening elements, when the skirt is open to hang freely, will fold inwardly toward the body of the user, permitting the opposite free terminal or edge portions of the ruffles to meet and overlap to give the appearance of a skirt circumferentially continuous throughout the full depth thereof. Correspondingly when the front and rear portions of the skirt are united beneath the crotch, the terminal or edge portions of each individual ruffle will meet and overlap lengthwise of and along the inside of the leg of the wearer to present the appearance of separate circumferentially continuous leg portions of drawers.

As observed in the fore part of this specification, the freedom of the inside edge portions of the legs,—indicated at U,—when my garment is made to serve as drawers, is important for this reason: Whereas the great depth of the formed crotch portion of the garment by reason of the low point of fastening at the bottom of the skirt, and the unusual width of the drawers legs, because of the conversion of a full width skirt thereinto, will assist materially in sanitary uses of the garment without the necessity of unfastening, yet the separation or splitting of the inner sides of the legs will add in substantial measure to the ease and assurance of shifting and adjusting the garment from side to side, dependent upon which particu-

lar leg opening is to be utilized, to give better protection for the leg portions, than would be afforded by a garment wherein the legs or ruffle extensions were endless or with their inner edge sewed together or otherwise fastened.

While I have herein disclosed one particular embodiment of the invention, it will be appreciated by persons skilled in the art to which the invention relates, that the same may be embodied in other forms incorporating such changes and alterations as may fall within the scope of the hereto appended claims.

Having thus described the invention, what I claim is:

1. A woman's undergarment of the character described comprising a skirt of relatively short length having a circumferentially continuous body portion extending to approximately the bottom of the skirt, a pair of ruffle extensions on said body each extending around one side and about half of the front and back of the garment and terminating centrally of said front and back to separate said extensions, and separable fastenings on the body immediately adjoining the terminal portions of the ruffle extensions for detachably securing together the front and back portions of the garment at said bottom thereof above the ruffle extensions, and to bring the respective pairs of depending ruffle terminal portions together to constitute correspondingly substantially complete separate leg extensions. 100

2. A woman's undergarment of the character described comprising a skirt of relatively short length having a circumferentially continuous body portion extending to approximately the bottom of the skirt, separable fastenings on the body at said bottom portion for detachably securing together the central parts of the front and back portions to the bottom to bring to direct meeting relation depending portions of the skirt to form substantially closed legs independent of the securing means, the members of said separable fastenings being located and formed to present no depending projections below the bottom edge of the skirt when 115 open.

3. A woman's undergarment of the character described comprising a skirt of relatively short length having a circumferentially continuous body portion extending to approximately the bottom of the skirt, separable fastenings on the body at said bottom portion for detachably securing together the central parts of the front and back portions of the bottom to bring to direct meeting relation depending portions of the skirt to form substantially closed legs independent of the securing means, the members of said separable fastenings being located and formed to present no depending projections 125 130

- below the bottom edge of the skirt when open, those parts of the front and rear portions carrying the fastening members being adapted each to close upon itself to obscure the said fastening members.
4. A woman's undergarment of the character described comprising a skirt of relatively short length having a circumferentially continuous body portion extending to approximately the bottom of the skirt, separable fastenings on the body at said bottom portion for detachably securing together the central parts of the front and back portions of the bottom, the members of said separable fastenings being located and formed to present no depending projections below the bottom edge of the skirt when open, those parts of the front and rear portions carrying the fastening members being adapted each to close upon itself to obscure the said fastening members, in combination with a pair of ruffle extensions on the body terminating at the center of the front and back portions also adapted to close together to present the appearance of an endless ruffle when the skirt is open and individual endless separate leg ruffles when the same is closed.
5. A woman's undergarment of the character described comprising a skirt of relatively short length having a circumferentially continuous body portion extending to approximately the bottom of the skirt, separable fastenings on the body at said bottom portion for detachably securing together the central parts of the front and back portions of the bottom, the members of said separable fastenings being located and formed to present no depending projections below the bottom edge of the skirt when open and to be united adjacent to the inner sides of the legs of the wearer when closed at points above separate substantially closed depending leg portions formed by bringing into direct closed relation opposite portions of the skirt.
6. A woman's undergarment of the character described comprising a skirt of relatively short length having a circumferentially continuous body portion extending to approximately the bottom of the skirt, separable fastenings on the body at said bottom portion for detachably securing together the central parts of the front and back portions of the bottom and to be united adjacent the inner sides of the legs of the wearer when closed at points above separate substantially closed depending leg portions formed by bringing into direct closed relation opposite portions of the skirt.
7. A woman's undergarment of the character described comprising a skirt of relatively short length having a body portion, and means for securing the front and back of the body portion together in drawer fashion at a point to leave depending open

inner-sided leg extensions, the free open inner edges of the extensions being parallel and closed together to constitute substantially complete leg portions.

8. A woman's undergarment of the character described comprising a body portion and short leg portions simulating skirt-like drawers, the inner sides of the leg portions being slit for a substantial distance upwardly from the bottoms thereof and detachable crotch closing parts above said slit portions and in line therewith.

9. A woman's undergarment of the character described comprising a body portion and short leg portions simulating skirt-like drawers, parts of the leg portions being slit for a substantial distance upwardly from the bottoms thereof and detachable closing parts above said slit portions and in line therewith.

10. A woman's garment of the character described comprising a skirt of relatively short length having a body portion, and means underneath the crotch for securing the front and back of the body portion together in drawer fashion at a point above depending free extensions constituting substantially complete open inner-sided leg portions.

11. A woman's garment of the character described comprising a skirt of relatively short length having a body portion, and means underneath the crotch including a rearwardly projecting flap for securing the front and back of the body portion together in drawer fashion at a point above depending free extensions constituting substantially complete open inner-sided leg portions.

12. A woman's garment of the character described comprising a skirt of relatively short length having a body portion, and means underneath the crotch including a rearwardly projecting V-shaped flap for securing the front and back of the body portion together in drawer fashion at a point above depending free extensions constituting substantially complete open inner-sided leg portions.

13. A woman's undergarment of the character described comprising a skirt of relatively short length having a body portion, and means adapted to be located underneath the crotch for securing at a concealed point the front and back of the body portion together in drawers fashion to constitute separate legs having substantially closed parallel inside and outside edges.

14. A woman's undergarment of the character described comprising a skirt of relatively short length having a body portion, and means near the bottom edge of the skirt for detachably securing the front and back thereof together below the crotch to bring into direct meeting relation depending por-

tions of the skirt to form substantially closed legs independent of the securing means at the crotch.

15. A woman's undergarment of the character described comprising a skirt of relatively short length having a body portion, and means near the bottom edge of the skirt for detachably securing the front and back thereof together below the crotch to bring into direct meeting relation depending portions of the skirt to form substantially closed legs independent of the securing means at the crotch, said means being arranged to remain in a position above the lower margin of the skirt when in open position.
